UNITED STATES PATENT OFFICE

110,743

DESIGN FOR A BEVERAGE COOLER CABINET

Everett Worthington, New York, N. Y., assignor to The Coca-Cola Company, Wilmington, Del., a corporation of Delaware

Application January 8, 1938, Serial No. 74,158

Term of patent 14 years

To all whom it may concern:

Be it known that I, Everett Worthington, a citizen of the United States and resident of New York, New York County, New York, have invented a new, original, and ornamental Design for Beverage Cooler Cabinets, of which the following is a specification, reference being had to the accompanying drawings, forming part thereof.

Fig. 1 is a front perspective view of the beverage cooler cabinet, showing my design;

Fig. 2 is a top plan view;
Fig. 3 is a front elevational view;
Fig. 4 is a rear elevational view thereof.
I claim:
The ornamental design for a beverage cooler cabinet, as shown.
